C. E. KELLER

UMBRELLA DOCK

Filed July 3, 1923

UNITED STATES PATENT OFFICE.

CARL E. KELLER, OF PITTSBURGH, PENNSYLVANIA.

UMBRELLA LOCK.

Application filed July 3, 1923. Serial No. 649,194.

To all whom it may concern:

Be it known that CARL E. KELLER, citizen of the United States, residing at Pittsburgh, in the county of Allegheny and State of Pennsylvania, has invented certain new and useful Improvements in Umbrella Locks, of which the following is a specification.

This invention relates to umbrella locks and has particular reference to the provision of means for effectively locking the ribs of an umbrella in lowered position alongside the umbrella stick whereby unauthorized use of the umbrella will be prevented.

An object of the invention is to provide a device of the above kind embracing the desired qualities of simplicity of construction, and efficiency in operation.

Another object of the invention is to provide a durable lock of the above kind capable of being easily and cheaply manufactured as well as readily placed into practical use.

Other objects will appear as the nature of the invention is better understood and the same consists in the novel form, combination and arrangement of parts herein-after more fully described, shown in the accompanying drawings, and claimed.

In the drawing, wherein like reference characters indicate corresponding parts throughout the several views,

Figure 1 is an elevational view of the inner disc in open position,

Figure 2 is a view similar to Figure 1 of the outer disc,

Figure 3 is a side elevational view showing the discs assembled with the locking device in unlocked condition,

Figure 4 is a view similar to Figure 3 showing the device in locked condition,

Figure 5 is an enlarged fragmentary sectional view taken substantially on line 5-5 of Figure 4, and

Figure 6 is a fragmentary side elevational view of an umbrella having the ribs thereof locked in lowered position by means of the device shown in Figure 4.

Referring more in detail to the drawings, the device consists of an inner disc embodying two half sections 5 and 6 hinged together as at 7 so that when closed, the free radial edges thereof will come flush together. The outer periphery of these disc sections are provided with notches 8, one for each rib of the umbrella, and these disc sections

are held together by means of a steel rib 9 which is fastened to one of the disc sections and on the end of which is a small head or ball 10 which fits into a hole 11 provided in the other disc section.

Around the inner disc is a channel shaped outer or collar disc also made of two half sections 12 and 13 and which are also hinged together as at 14. Each side of each of the sections 12 and 13 is hinged separately so that the inner disc may be readily inserted in the outer disc composed of the sections 12 and 13. The outer periphery of the outer or collar disc is formed with under cut notches as at 15 to correspond with the number of notches on the inner disc, and elongated slots 15 are provided through both sides of the collar disc coincident with similar slots 16 provided through the inner disc. Pins 17 extend through aligned ones of these slots, and have their ends flattened to form heads which hold the two discs together.

These disc sections 6 and 13 are provided with cooperating holes 18 and 19 respectively, adapted to receive the shackle of a small padlock when the discs are positioned as shown in Figure 4 for locking them against relative turning with the notches 8 closed by the overhanging portions of the outer disc which are presented by the under cutting of the notches of said outer disc. The inner disc is provided with a central opening as at 20 for reception of the umbrella stick onto which the device may be readily placed when the discs are swung to open position about the hinges 7 and 14, and the outer disc is also provided with a central opening as at 21 which is preferably larger than the opening 20 so as to form clearance for the rib 9 of the section 5.

Figure 4 shows the two discs assembled and the notches on the inner disc closed by the collar disc. This is accomplished by sliding or revolving the collar disc around to the right on the inner disc. When the collar disc is slid around and the notches completely closed on the inner disc, the holes 18 and 19 of the discs align themselves so that a small padlock 22 may be snapped onto the discs with its shackle extending through the holes 18 and 19. Each rib of the umbrella may thus be firmly locked in a separate closed notch, and the balls on the inner ends of the ribs prevent the ribs

from being sprung and pulled out of the locking device.

The discs are to be made as small as is practicable and of some suitable non-flexible material.

From the foregoing description it will be seen that I have provided a locking device which will discourage the petty theft of umbrellas and also will reduce the number of 10 umbrellas lost by being taken by mistake. The device could be included in the equipment of an umbrella, in which case each disc could be made in one piece and put on the umbrella at the factory.

15 Minor changes may be made without departing from the spirit and scope of the invention as claimed.

Having thus described my invention, what I claim as new and desire to secure by Letters Patent is:

20 1. Means for locking the ribs of an umbrella comprising a collar composed of two discs relatively rotatably mounted to encircle the stick of the umbrella, the inner disc having notches for the reception of the umbrella ribs, the outer disc having under cut notches whereby the notches of the inner disc will be closed when the discs are rotated relative to each other, and means for locking said discs against relative rotation when the notches are closed.

25 2. Means for locking the ribs of an umbrella comprising a collar composed of two discs relatively rotatably mounted to encircle the stick of an umbrella, the inner disc having notches for the reception of the umbrella ribs, the outer disc having under cut notches whereby the notches of the inner disc will be closed when the discs are rotated relative to each other, means for locking said discs against relative rotation when the notches are closed, said discs each comprising 30 half sections hingedly connected together

for permitting the engagement of the device with the umbrella stick, and means for holding said discs in closed position. 45

3. Means for locking the ribs of an umbrella comprising a collar composed of two discs relatively rotatably mounted to encircle the stick of the umbrella, the inner disc having notches for the reception of the umbrella ribs, the outer disc having under cut notches whereby the notches of the inner disc will be closed when the discs are rotated relative to each other, means for locking said discs against relative rotation when the notches are closed, said discs each comprising 50 half sections hingedly connected together to permit the attachment thereof to the umbrella stick, means for holding said discs in closed positions, and means for limiting the relative movement of said discs. 55

4. A rib locking device for umbrellas comprising an inner disc adapted to encircle the stick of an umbrella and provided with peripheral notches adapted for reception of the ribs of the umbrella, and an outer disc revolvably carried by the inner disc having peripheral under cut notches whereby the rotation of the outer disc relative to the inner disc will close the notches therein. 60

5. A rib locking device for umbrellas comprising an inner disc adapted to encircle the stick of an umbrella and provided with peripheral notches adapted for the reception of the ribs of the umbrella, and an outer disc revolvably carried by the inner disc having peripheral under cut notches whereby the rotation of the outer disc relative to the inner disc will close said notches of the inner disc, 65 and means to lock the disc in rib engaging and retaining position against relative rotation. 70

75 In testimony whereof I affix my signature.

CARL E. KELLER.
